(57) **CLAIM**

The ornamental design for an endotracheal tube, as shown and described.

DESCRIPTION

FIG. 1 is a side view of a right side of an endotracheal tube with a radiopaque chevron shaped biocompatible marker at a distal end and a series of dots.

FIG. 2 is a top view of an endotracheal tube with a radiopaque chevron shaped biocompatible marker at a distal end and a series of dots.

FIG. 3 is a bottom view of an endotracheal tube with a radiopaque chevron shaped biocompatible marker at a distal end and a series of dots; and,

FIG. 4 is a side view of an endotracheal tube shown in a condition of use.

The broken lines shown in FIG. 2 illustrate portions of the endotracheal tube that form no part of the claimed design. The broken lines shown in FIG. 4 illustrate environment and form no part of the claimed design.

1 Claim, 3 Drawing Sheets
